ANTISIPHONING MEANS FOR DISHWASHING MACHINES

Raymond W. Wilson, Glendale, Calif.

Application September 27, 1944, Serial No. 555,983

2 Claims. (Cl. 134—141)

1

The present invention relates to improvements in antisiphoning means for washing machines and particularly to a conduit structure embodying such a means applicable to a machine of the dishwashing class as disclosed in Patent #2,315,572 issued to me April 6, 1943.

Under certain unusual conditions according to the health authorities it is possible to have a vacuum occur at the water valve instead of the usual pressures so that if certain conditions obtain, contaminated water from the drain, tub or piston chamber might be drawn into the city water lines which is forbidden.

An air gap positioned between the aforementioned parts would render such a feedback impossible.

One of the objects of the invention is to provide a conduit structure for washing machines which will prevent any possibility of a cross flow connection being made between the city water supply which operates the device and the drainage or sewage system whereby foul water might be siphoned back into the main supply line and contaminate it due principally to the unusual conditions aforementioned.

A further object is to improve upon the sanitary conditions relating to devices to which this invention appertains.

A further object is to provide improved means whereby a lower point of overflow of a backed-up sewer is effected than the normal rim overflow of the fixture communicating with the sewer.

A further object is to provide improved means to indicate when a defectiveness exists in certain of the associated plumbing parts.

A still further object is to provide improved means for obtaining a more positive purging and cleansing of certain parts of the apparatus with which the conduit structure is connected.

Yet a further object is to be able to ascertain when serious leaks occur in certain gaskets by observing discolorations in the water passing by the sight opening in the antisiphoning device which the liquid spirits past.

Other objects, advantages and features of invention will hereinafter appear.

Referring to the drawing which illustrates what at present is deemed to be a preferred embodiment of the invention,

Fig. 1 is a fragmentary plan view of a sink and 50 The hydraulic lift 16 will be seen, by referring

2

dishwashing machine with which the conduit structure is related, the dish basket being removed and certain portions being broken away to disclose underlying structures.

5 Fig. 2 is a vertical section taken on line 2—2 of Fig. 1 showing the conduit structure connected to the dishwashing machine, the dish basket being added in this view and shown in dotted and full lines in two different positions.

10 Fig. 3 is an enlarged elevational view of an antisiphoning means forming a part of the conduit structure, some parts being broken away and other parts sectioned.

Fig. 4 is a horizontal section taken on line 4—4 of Fig. 2.

15 Fig. 5 is a transverse section taken through the three way valve shown in Figs. 1 and 2.

Fig. 6 is a fragmentary, vertical cross section taken through the lower end of the hydraulic lift.

20 Referring in detail to the drawing, therein is shown a sink 6 having associated therewith a hydraulically operated dishwashing machine 7, the sink emptying into a pipe 8 and the dishwashing machine emptying into a pipe 9, both of said pipes leading through the trap 10 into the sewage line.

25 There is a hot and a cold water supply line connected to the sink, the hot and cold water conduits being indicated respectively by the numerals 11 and 12. Conduit 13 connects the cold water line with a three way valve 14 situated at the right-rear of the wash tub 15 shown in Figs. 1 and 2.

30 To the underside of the tub 15 is shown connected the hydraulic lift 16 which actuates, through the medium of the water pressure, the upward movement of the dish basket 17.

Conduit 18 connects the three way valve 14 with the lower end of the lift 16, and conduit

35 19 connects the three way valve with the upper portion of the lift, the connection 20 of conduit 19 with the lift being shown on an increased scale in Fig. 4. Diametrically opposite to the connection 20 just described is a second connection 21 which is connected to conduit 22 and the latter conduit in turn is connected to the antisiphoning means 23 by an L 24. Connections 20 and 21 communicate with an annular space 25 surrounding the plunger 26.

to Fig. 6, to include the cylinder 30 and the plunger 26 closed by the cap 32 screwed thereto, a pin 38 being secured to the cap to anchor the lower end of the spring. A double gasket 34 is shown sealing the annular chamber 25 from the fresh water supply, the pressure from which exerts a force against the plunger to elevate it, the spring 16s restoring it to normal position as soon as the three way valve is operated to relieve such pressure.

When port 35 is in registry with conduit 19 as shown in Fig. 5, the dish basket is in position to be elevated as soon as the three way valve is operated to bring the restricted port 36 in communication with conduit 18, port 36 being purposely made smaller in size to cause a slower elevating movement of the dish basket.

When the three way valve is in the position shown in Fig. 5, the fresh water from conduit 18 is discharged through conduit 19 around the annular passage 25, as seen in Fig. 4, to the opposite conduit 22 and thence through the antisiphoning device 23 into the pipe 9 leading to the sewer. Hence it will be observed that any leak to the annular space 25 from the tub 15 can be detected owing to the discoloration of the water by looking at the discharged water as it flows past the air gap provided by the diametrically opposite openings 37 in the antisiphoning device. This leak and discoloration of the water would not be so readily apparent if such discharge were partially by-passed by the annular chamber 25 as shown by the T arrangement in the stated patent. Neither would the chamber 25 be purged and cleansed so readily for the same reason. Furthermore by looking into the sight opening or air gap 37 any drippage passing therewith when the device is not in operation will indicate faulty construction in the three way valve and plunger gaskets and the necessity for making immediate repairs.

The antisiphoning device 23 further comprises a water reservoir or tank 40 which is closed at its lower end by a cap 41 and a conduit connection 42 is shown in Fig. 2 attaching said cap to the pipe 9 in such a manner as not only to provide communication therebetween but also it serves as an auxiliary support for the tank 40, a main clamp 43 being shown embracing the tank 40 and secured to the outside wall of the tub 15 in any suitable manner to provide the main brace and support for the antisiphoning means.

A reduction coupling 44 is screwed onto the upper end of the tank 40 and into the upper end of the coupling is screwed the threads of the thimble 45 provided with the already mentioned sight openings or air gap 37, one end of the L connection 24 being screwed into the upper end of said thimble.

Onto the externally threaded end of the thimble is first screwed an annular sump cup 46 before the thimble is finally screwed into the coupling 44 and after the latter connection has been made the cup 46 is screwed tightly against the upper face of the reduced part of the coupling, there being diametrically opposite holes 47 in the thimble to drain the sump when splash through the oppositely directed openings 37 from the liquid spouting past the openings collects in the sump cup.

Tank 40 is essentially made large owing to the fact that the discharge under pressure thereto is greater than that egressing through the connection 42 into the drain pipe 9. The openings 37 are large, also are located far below the

rim line of the tub so that overflow of backed-up sewage will flow out through said openings into a suitable receptacle placed there for that purpose before the tub proper could overflow thus indicating the feedback condition of the sewer.

Conversely, should a vacuum occur in the main water supply at a time when the basket 17 is in the raised position and the valve 14 at such time is in the position placing supply line 13 in communication with pipe 18, the internal spring 16s would force the water out of the cylinder 30 and back into the main supply line augmented by the suction pull. Should this condition arise simultaneously wherein the gasket 34 was defective and a backed-up condition of the drain pipe 9 was occurring, in such instance in all probability, impurities could be conveyed from the latter pipe through the line 21 into the cylinder 30 past such defective gasket 34 and into the main supply as aforesaid or similarly in applicant's patented device supra, were it not for some antisiphoning device like that of 23 placed in the path of flow. Such an antisiphoning device meets the requirement in connection with washing machines installed in localities demanding rigid enforcement of the sanitary code.

It should be understood that the present disclosure is for the purpose of illustration only and that this invention includes all modifications and equivalents which fall within the scope of the subject matter claimed.

What is claimed is:

1. In a washing machine having a tub, a pipe for supplying water thereto, a cylinder fixed to and depending from the bottom of the tub, a plunger mounted to reciprocate vertically in said cylinder and carrying a basket movable in the tub, valve controlled conduit means for selectively connecting the bottom of the cylinder with the water supply pipe and with the upper part of the cylinder for respectively elevating the plunger and basket and for lowering the same, a tank supported exteriorly of the tub with its bottom end at a level below the bottom of the tub and its upper part at a level above the bottom of the tub, the upper part of said tank being provided with openings in the side walls thereof, a pipe connecting the upper part of said cylinder with the top of said tank so that matter discharged from the upper part of said cylinder will be caused to flow downward through and can be observed through the openings in the tank, and a pipe connecting the bottom of the tank with a sewer line.
2. In a washing machine having a tub and a fresh water supply line thereto, a cylinder secured to and depending from the bottom of the tub, a vertically reciprocating plunger mounted within said cylinder and spaced therefrom to provide an interior chamber, packing fixed about the lower end of said plunger, a basket fixed on said plunger, a tank supported exteriorly of the tub with its bottom end at a level below the bottom of the tub and its upper part disposed in a position intermediate the top and bottom of the tub, said upper part of the tank having sight openings in opposed sides thereof, a pipe connecting the bottom of said cylinder with a control valve, a supply pipe connecting the water supply line with said control valve, a pipe connecting the upper part of said cylinder with the control valve, said control valve being operable to selectively connect the pipe to the bottom of the cylinder with the supply pipe and to the pipe connecting with the upper part of the cylinder,

for respectively raising and lowering the plunger, a discharge pipe connected to the cylinder at approximately the level of the connection of the pipe connecting with the upper part of the cylinder, said discharge pipe having its opposite end connected to the top of said tank so that fluid discharged from the cylinder is caused to flow down past the sight openings in the upper part of said tank, and a pipe connecting the bottom of said tank with a sewer line.
